UNITED STATES PATENT OFFICE

2,247,189

CARBURETOR

Clement de Guyon, Hartford, Conn.

Application July 23, 1940, Serial No. 347,073

1 Claim. (Cl. 261—51)

This invention relates to carburetors for internal combustion engines, and has for the primary object the provision of a device of this character which will admit fuel to an air and fuel mixing chamber by the opening and closing of the throttle valve so as to supply fuel mixture to the engine to meet varying loads on said engine and will render the engine easy to start and eliminate customary choke valves, float valves and associated parts now employed in carburetors used on engines.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a top plan view illustrating a carburetor constructed in accordance with my invention.

Figure 2 is a vertical sectional view taken on the line 2—2 of Figure 1.

Figure 3 is a sectional view taken on the line 3—3 of Figure 2.

Figure 4 is a top plan view illustrating a modified form of my invention.

Figure 5 is a vertical sectional view taken on the line 5—5 of Figure 4.

Figure 6 is a sectional view taken on the line 6—6 of Figure 5.

Figure 7 is a detail transverse sectional view illustrating a metering pin sleeve and its mounting within a metering pin cage.

Referring in detail to the drawings, the numeral 5 indicates the body of the carburetor composed of sections A and B. An external sleeve 6 is shrunk on the section A and has a telescopic fit with a portion of the section B and is detachably secured thereto by fasteners 7.

The section B has a portion thereof shaped to form a throat 8, flanged, as shown at 9, to permit coupling of the throat onto an intake manifold of an internal combustion engine. A throttle valve 10 of the butterfly valve type is journaled in the throat 8 and the shaft thereof is indicated by the character 11. The shaft 11 is equipped with an operating arm 12 and a stop means 13 for limiting the closing of the throttle valve so that an engine may be kept running at idling speed. Also, the throttle valve is equipped with ports 14 to permit sufficient fuel

mixture to pass the throttle valve when the latter is in a closed position to maintain the engine operating at idling speed.

It is to be understood that the arm 12 is connected to the usual throttle operating means for the carburetor.

The section B of the body 5 is further provided with a flared chamber 15 coaxing with a flared chamber 16 in the section A of the body in defining a combined air and fuel mixing chamber.

By referring to Figure 2 it will be seen that the flared chamber of the section B leads into the throat 8 while the walls of the chamber 16 of the section A of the body have a series of air ports 17 connecting with an air chamber 18 formed in the section A of the body.

The section A of the body 5 has formed therein an annular recess closed by the sleeve 6 to form the air chamber 18. The air chamber is in communication with the atmosphere by way of a series of passages 19 formed in the section A of the body 5 and opening outwardly through the upper end of the latter. By referring to Figure 1 it will be seen that these passages 19 may be of varying sizes.

The section A of the body 5 is recessed to form a nozzle chamber 20 in which is threaded a nozzle 21. Interposed between the inner wall of the nozzle chamber and the nozzle 21 is a gasket 22, spacing the nozzle 21 a limited distance away from the inner wall of said nozzle chamber to form an air chamber connecting with an air passage 23 opening outwardly through one side of the section A and the sleeve 6 and in which is threaded a conduit 24 employed for introducing air under pressure from a conventional type of air supercharger.

The nozzle 21 is recessed to form a dome shaped chamber 25 connecting with the air and fuel mixing chamber. The chamber 25 is connected to the air chamber of the air supercharging passage 23 by ports 26 set at an inclination and converging towards each other where entering the chamber 25 so that the air under pressure will be delivered in the chamber 25 towards the center thereof.

The section A of the body 5 is provided with a metering pin chamber 27 in which is mounted a sleeve 28 having a rounded closed end 29 seated within a cup-shaped recess 30 formed centrally of the nozzle 21. The rounded closed end 29 of the sleeve has a metering pin neck 31 which extends through a centrally arranged port in the nozzle to deliver fuel into the chamber 25

centrally thereof for mixing with the air received by way of the ports 26 and 47. The neck 31 forms a seat for a metering pin 33 slidably mounted within an inner sleeve 34 mounted in the sleeve 28 and spaced therefrom by upper and lower collars 35 and 36. The lower collar 36 has a series of notches 37 to permit fuel to pass the lower flange and reach the neck 31 of the outer sleeve 28. It is to be understood that fuel under pressure is admitted to the outer sleeve 10 by the port 28', the latter being connected to a feed pressure source (not shown) in any well known manner. The flange 35 is also provided with notches to permit the fuel to pass down between the sleeve 34 and the sleeve 28. The 15 inner sleeve 34 projects above the outer sleeve 28 and has arranged between its upper end and the metering pin chamber 27 a packing 38 through which the metering pin 33 extends.

The section A of the body 5 is recessed, as 20 shown at 39, to receive the upper end of the metering pin and in which extends an operating lever 40 pivoted on the sleeve 6, as shown at 41. The sleeve 6 has a slot to permit the lever 40 to extend therethrough. It is preferable that the lever be composed of sections having telescopic fit with each other. One end of the lever 40 is pivoted to the metering pin and the other end is pivotally connected to an adjustable connecting link 42 which is in turn pivotally connected onto an arm 44 forming an integral part of the operating arm 21 of the throttle valve so that as the throttle valve is moved away from a closed position, the metering pin also will be moved away from its seat to admit fuel to the air and fuel mixing chamber and as the air passes into said chamber from all sides and the fuel centrally thereof, the fuel and air will become thoroughly mixed and rendered volatile to provide proper fuel mixture for the engine.

As indicated at 45, fuel is forced into the metering pin chamber 27 under pressure. It will be seen that the construction of carburetor described will eliminate the use of a choke and also a float valve and associated parts and that the fuel will be proportionately admitted to the mixing chamber as the throttle valve is moved towards open and closed positions.

Referring to my modified form of my invention, the body of the carburetor is indicated by the character 46 and is composed of detachably connected sections C and D and the section D is constructed similarly to the section B of the body 5, the throttle valve being indicated by the character 47. Also it will be noted that the sections C and D are detachably connected in the same manner as the sections A and B.

The section C has a metering pin chamber 48 fed with fuel by way of the passage 49, it being understood that fuel is fed into the metering chamber under pressure. Also, it will be seen that the chamber 48 is provided with the metering pin sleeves 28 and 36 and the metering pin 33. It is to be noted that the metering pin in either form of the carburetor is urged into seated position by the action of a coil spring 49. The connection between the metering pin 33 of my modified form of the invention with the throttle valve is similar to the connection provided in the form of my invention shown in

Figures 1 and 2 and it is, therefore, not thought necessary to again describe this construction in detail.

The section C of the body 46 is provided with 5 a comparatively large recess in which is threaded a nozzle 50 having a gasket 51 interposed between itself and the inner wall of the recess. Between the nozzle and the body is defined an air chamber 52 fed with atmospheric air by way of passages 53 opening outwardly through the upper end of the section C of the body 46. The nozzle 50 is provided with a dome-shaped portion 52' coacting with the flared recess 53 in the section D in forming the air and fuel mixing chamber. The dome-shaped portion of the nozzle has formed therein a series of ports 54 connecting with the air chamber 52. It will therefore be seen that the air is admitted into the air and fuel mixing chamber in converging relation and towards the center of said chamber. Also it will be noted that in this form of the invention the fuel is admitted to the dome of the nozzle centrally of the dome portion so that fuel will be delivered axially of the air and fuel mixing chamber with the incoming air converging from all sides of the flow of fuel and thereby bring about a rapid and thorough commingling of the air and fuel to produce a desired fuel mixture for an engine.

30 By referring to Figures 2 and 5 of the drawings it will be seen that both forms of my invention operate on the downdraft principle and choke valves, float valves and associated parts are unnecessary and that the engine will receive 35 fuel mixture in accordance with its loads.

While I have shown and described the preferred embodiment of my invention, it will be understood that minor changes in construction, combination and arrangement of parts may be made without departing from the spirit and scope of the invention as claimed.

Having thus described the invention, what I claim is:

In a carburetor, a body including recessed 45 separable upper and lower sections arranged in vertical endwise relation and coacting to provide a mixing chamber and a throat with the mixing chamber extending into both of said sections, the upper section having an air chamber, a coupling sleeve detachably joining said sections, means for admitting air to the air chamber, a throttle valve for controlling the throat, an annular member threaded in and located at the upper end of the mixing chamber and including 50 a substantially dome-shaped portion having a centrally arranged opening and a plurality of ports grouped annularly about the opening, and connecting the air chamber to the mixing chamber for directing air into said mixing chamber axially thereof, said dome-shaped portion having a seat in the upper face thereof, a fuel sleeve mounted in the upper section and having a rounded end engaging the seat and provided with an outlet neck extending through the opening and providing a valve seat, means for admitting liquid fuel to said fuel sleeve, and a spring influenced metering pin connected to and operated by the throttle valve and supported in the sleeve for coaction with the valve seat to control liquid fuel into the mixing chamber axially thereof.
